2 SHEETS—SHEET 2.

UNITED STATES PATENT OFFICE.

PERCY ST. GEORGE KIRKE, OF WESTMINSTER, LONDON, ENGLAND.

STEAM-SUPERHEATER.

1,335,974.

Specification of Letters Patent.

Patented Apr. 6, 1920.

Application filed August 7, 1917. Serial No. 184,944.

To all whom it may concern:

Be it known that I, PERCY ST. GEORGE KIRKE, a subject of the King of Great Britain and Ireland, and resident in the city of 5 Westminster, London, England, have invented new and useful Improvements in or in Connection with Steam-Superheaters, of which the following is a specification.

This invention has relation to the production of superheated steam, and has reference in particular, but not exclusively, to the superheating of steam generated by the heat produced by burning a mixture of gaseous fuel and air on the surface of, or 15 in the neighborhood of, an incandescent body placed within a boiler fire tube.

The invention is applicable to steam generators of the type in which hot products of combustion pass through tubes or flues, 20 such tubes or flues, herein called tubes, being in contact on their outer surfaces with the water, and being packed or charged with packing material, which accelerates the transmission of the sensible heat in the gases and combustion products in passing through 25 the spaces between the packing material and the tubes to the water in the steam generator.

Steam superheating arrangements in accordance with this invention, comprise boiler tubes, each in part packed or charged for a portion of their length with packing material in contact with, or in the neighborhood of which combustion of the gaseous fuel may 35 take place, superheating coils arranged within another portion of each of said tubes, and further partly filling packing material in the remainder of said tubes so as to reduce the temperature of the gases and combustion products to a few degrees above that 40 of the saturated steam.

The accompanying drawings illustrate a gaseous fuel fired steam generator of the kind referred to provided with superheating arrangements in accordance with this invention.

Figure 1 is a longitudinal sectional view; and

Fig. 2 is an end elevation.

Fig. 3 is a detail view of the refractory material.

Fig. 4 is a sectional view of the packing material.

1 is the shell of the steam generator in 55 the end plates of which are secured the ends of a plurality of tubes 2 through which the

hot products of combustion pass. The tubes 2 are packed or charged from one end for a portion of their length with refractory material 3 so as to only partially obstruct 60 the passage of the flue gases, preferably as described and claimed in the specification forming part of an application for Letters Patent Serial No. 132,448, dated 20th November, 1916, and filed by the applicant 65 herein. The refractory material 3 is shown in Fig. 1 to consist of rectangular blocks twisted with respect to each other in step wise form in order to form a sinuous path for the gases to the boiler tubes 2. The 70 length of the blocks is shown to be substantially that of the diameter of the tubes and the end on width about one-third of the length of the blocks. 4 are gaseous fuel supply nozzles, there being a nozzle for each 75 tube 2. Gaseous fuel is supplied to the nozzles 4 through a main 5 and is regulated by a valve 6. The gaseous fuel from the nozzles 4 and air are induced into mixing chambers 7, with which the one end of each 80 tube 2 is provided, and to form therein a combustible mixture, combustion of which is completed in contact with, or in the neighborhood of, the refractory material 3, all in manner well understood.

8 are the superheated coils. These coils 8 are inserted within, and from the opposite end of, the tubes 2 so as to occupy positions therein adjacent the refractory material 3. The remainder of the length of each tube 2 90 is filled with further packing material 9 so as to only partially obstruct the passage of the flue gases. The superheated coils 8 extend backward and forward of the tubes 2, and each coil is connected at one end to a 95 header 10 in connection with the source of saturated steam and at the other end to a header 11 in connection with the steam engine or other means in which the superheated steam is utilized.

The packing material 9 is shown pointed against the direction of the flow of the gases, so that any dust contained in the gases may pass out of the end of the boiler tubes 2. The refractory material 9 may be of 105 varying shape, but a conical or cylindrical shape having wings 9^a to enable it to be inserted approximately concentric with the tube axis is preferred, slots being also formed in it to receive the superheated inlet and outlet tubes. Or the packing material 9 may be cut away on its lower portion

and the superheater inlet and outlet tubes led through the space formed by and between the wall of the tube 2 and the packing material 9. The packing material 9 contained in each tube 2 may be in one length if desired, and as the temperature at this point is comparatively low, it may be made of metal, if preferred. The distance between the headers 10, 11 and the ends of the tubes 2 is preferably made longer than each piece of packing material 9, so that the latter can be inserted and extracted without removing the headers. Or, as shown, the headers 10, 11 may be so disposed and arranged as not to interfere with the insertion and extraction of the packing material.

The object of the packing material 9 is to enable the gases to have their heat efficiently abstracted by the superheater present.

What I claim is:—

1. A boiler heating and superheating system comprising a boiler, a passage for hot gases within said boiler, said passage having

a refractory heating chamber for higher temperatures in communication with a steam superheating chamber, also forming part of said passage, a superheating means within said superheating chamber, and a second refractory chamber within said passage for lower temperatures and in communication with said superheating chamber.

2. In a steam superheating system, a passage for hot gases comprising a refractory chamber for higher temperatures having means therein to give a helical path to the hot gases, a steam superheating chamber in communication with said refractory chamber, a steam superheating means within said superheating chamber, and a second refractory chamber for lower temperatures in communication with the said superheating chamber and having means therein to give to the gases a substantially straight line path.

Dated this 6th day of July, 1917.

PERCY ST. GEORGE KIRKE.
